Int. Cl. D6—04

U.S. Cl. D6—149

The figure is a front perspective view of the hexagonal commode or the like showing my new design.

In the perspective of the hexagonal commode or the like showing my new design, the opposite view is substantially a mirror image of that shown.

The bottom of the hexagonal commode is substantially plain and unornamented.

I claim:

The ornamental design for a hexagonal commode or the like, as shown and described.
